By Oscar A. Taft. A.M.

UNITED STATES PATENT OFFICE.

ERNEST O. LAWTON, OF FITCHBURG, MASSACHUSETTS.

ADJUSTABLE SIGNAL-BLOWER.

No. 910,135.

Specification of Letters Patent.

Patented Jan. 19, 1909.

Application filed June 2, 1905. Serial No. 263,380.

To all whom it may concern:

Be it known that I, ERNEST O. LAWTON, of Fitchburg, in the county of Worcester and State of Massachusetts, have invented certain new and useful Improvements in Adjustable Signal-Blowers; and I do hereby declare that the following is a full, clear, and exact description of the same.

This invention relates to signals and particularly to adjustable audible signals and means for operating them.

An object of this invention is to provide novel means for blowing a horn, the said means being particularly designed for use in vehicles of the automobile type, whereby the device may be stationed under the floor of the vehicle body, an operating rod or handle being the only visible portion above the floor. As to the point of attachment of the operating mechanism, it is an immaterial feature, as I have provided means for adjusting the operating rod or plunger to suit particular requirements.

A further object of this invention is to provide a bellows or other compressing means so constructed as to prolong the durability of the material from which it is formed, and I provide novel means whereby the compressed air may be conveyed from the compressor to any suitable point where the sounder or horn is stationed.

Finally an object of this invention is to produce a device of the character described which will prove efficient and satisfactory in use, comprising comparatively few and inexpensive parts, and simple in construction.

With the foregoing and other objects in view, the invention consists in the details of construction and in the arrangement and combination of parts to be hereinafter more fully set forth and claimed.

In describing the invention in detail reference will be had to the accompanying drawings forming part of this specification wherein like characters denote corresponding parts in the several views, in which—

Figure 1, is a view in perspective, of the casing and the compressor operating means with the horn and connection to the compressor. Fig. 2, is a view in elevation of the casing broken away to show the compressor mechanism. Fig. 3, is an end view of the compressor casing and coupling. Fig. 4, is

a plan view with the top of the casing removed.

In these drawings A. denotes the casing, one end of which is provided with a vertically disposed slot B, through which the arm C, projects, and in which the said arm is slidable.

Within the casing and on the bottom thereof I provide a frame D, forming one portion of a bellows and to this frame I hinge a top E, through the medium of the hinges F.

The side and front edges of the frame D, and top E, are connected by a flexible wall G, which permits the top to descend with relation to the frame D, thereby compressing the air and forcing it out of the coupling H, which coupling is here shown as an L-shaped pipe having its upper end attached to the casing A, in any suitable manner, it being understood that the said coupling is in communication with the interior of the bellows, heretofore described.

The arm C, is attached to the top E, of the bellows and its movement is communicated to said top for the purpose of depressing it and the said top is held normally elevated through the medium of the spring I, which has one end connected to the arm C, and the opposite end connected to the cross-arm J, which is supported by the sides of the casing. The top of the bellows is also held elevated through the medium of the spring K which is arranged internally of the bellows on the studs L, which act as guides.

The outer end of the arm C, is provided with an aperture through which the rod M, is adjustable, it being understood that the lower end of the said rod is threaded for a suitable distance to permit the adjustment of the nuts, N, and N', stationed on opposite sides of the arm. If, therefore the casing containing the compressor is secured to the frame of the vehicle, the said casing may be positioned at a greater or less distance from the floor of the vehicle and the rod may be adjusted to project through the said floor by reason of the provision of the nuts indicated.

It will be observed that the rod may be shortened in like manner and therefore this compressor, may be changed as stated, to suit particular requirements. The head or

plunger body O, is threaded or otherwise removably secured to the rod to permit the said rod to pass through a small opening in the bottom of the body of the vehicle before the head is applied.

A flexible pipe P, is held in position by a bracket Q, and the horn R, may be made stationary through the medium of the apertured ear S, which is provided to receive 10 the screw or other binding agent.

The construction, operation and advantages will, it is thought, be fully understood from the foregoing description.

Having fully described my invention, 15 what I claim as new and desire to secure by Letters Patent, is—

In combination a casing having a vertical

slot in one end, a bellows in the casing, said bellows having opposed studs on the inner faces of the walls thereof, a spring engaging 20 the studs and holding the bellows normally distended, an air outlet tube, an arm secured to the upper face of the bellows and extending through the slot, a cross arm secured within the casing above the bellows, a spring 25 secured to said cross arm and the bellows to further hold the bellows distended and an adjustable rod carried by the arm on the bellows whereby the operation of the bellows may be regulated.
